(57) **CLAIM**

The ornamental design for a shoe sole, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a bottom view of a shoe sole, showing my new design;

FIG. 2 is a front view of the shoe sole shown in FIG. 1;
FIG. 3 is a side view of the shoe sole shown in FIG. 1;
FIG. 4 is a rear view of the shoe sole shown in FIG. 1;
FIG. 5 is the other side view of the shoe sole shown in FIG. 1;

FIG. 6 is a bottom perspective view of the shoe sole shown in FIG. 1; and,

FIG. 7 is a top perspective view of the shoe sole shown in FIG. 1, with upper shown in broken lines.

The broken line just within the perimeter of the top surface of the sole is the boundary between the claimed perimeter of the top surface of the sole and the unclaimed surface within the broken line boundary.

The stippling in FIGS. 1-7 reflect a color contrast from the red colored areas of the sole.
